SYLVANIA, A CORPORATION OF PENNSYLVANIA

ADJUSTING MEANS FOR HOSIERY STRIPPERS

Application filed February 29, 1932. Serial No. 595,879.

This invention relates to machines for removing stockings from forms such as that shown in United States Letters Patent No. 1,126,619, dated January 16, 1915, wherein a stocking or a form is placed between pairs of cooperating jaws arranged to grip the heel and foot portions respectively of the stocking and to hold such portions substantially stationary while the form is withdrawn from the stocking.

The object of the present invention is to correct certain faults that have been found in machines evolved from the original machine shown in the above noted Letters Patent, and which will be fully disclosed herein-after, reference being had to the accompanying drawings, of which:

Fig. 1 is a plan view of sufficient of the machine to illustrate the application of the present invention thereto;

Fig. 2 is a front elevation of the mechanism shown in Fig. 1;

Fig. 3 is a section taken on the line 3—3, Fig. 1, with the gripping jaws in the closed position;

Fig. 4 is a view similar to Fig. 3 with the gripping jaws in the open position;

Fig. 5 is a sectional elevation taken on the line 5—5, Fig. 1, with the elements arranged to open and close the jaws normally;

Fig. 6 is a sectional elevation taken on the line 6—6, Fig. 5;

Fig. 7 is a sectional plan view taken on the line 7—7, Fig. 6;

Fig. 8 is a view similar to Fig. 5, but showing certain of the elements in a position to prevent closing of the gripping jaws; and

Fig. 9 is a sectional plan view taken on the line 9—9, Fig. 8.

In the machine shown in the present instance, a stocking form with a stocking thereon is adapted to be placed between a pair of cooperating jaws 1 and 2 arranged to grip the foot portion of the stocking, and a pair of cooperating jaws 3 and 4 arranged to grip the heel portion of the stocking.

These grippers 1—2 and 3—4 are pivotally mounted on a non-rotating supporting rod 5. The jaws 1—2 and 3—4 are connected by

links, 6, 6 and 7, 7 to actuating levers 8, 8, secured to an actuating shaft 9.

The supporting rod 5 and the actuating shaft 9 are carried in a suitable support 10 and project laterally therefrom as shown in Figs. 1 and 2. The supporting rod 5 is held against rotation while the shaft 9 is adapted to be rocked about its own axis in the support 10 for opening and closing the gripping jaws as will be fully disclosed hereinafter.

The support 10 is arranged to be swung about a vertical axis, to assist in the removal of the form from the stocking and for this purpose is provided with a hub 11 rotatably mounted on the lower end of a boss 12 formed on the outer end of an arm 113 which in turn is adapted to be swung about a vertical axis coincident with the axis of the vertical shaft 14 shown in Fig. 1, to assist in the removal of the stocking from the form.

The swinging of the support 10 and its carrying arm 113 is accomplished by mechanism forming no part of the present invention, and for the purpose of simplicity is not shown in the present case.

The end of the actuating shaft 9, adjacent the support 10, is provided with a lever 13 pivotally connected at its outer end by a link 16 to the lower end of an actuating rod 17.

The rod 17 is provided with a head 17a on which rests the lower end of a sleeve 19, the upper end of which is provided with a spiral cam surface 20. The cam surface 20 coacts with a similar cam surface 21 formed on the lower end of a collar 22 which is rotatably mounted on the upper end of the rod 17 between the cam surface 20 of the sleeve 19 and a fixed abutment 18 on the extreme upper end of the rod 17.

When the collar 22 is in the position shown in Figs. 5, 6 and 7, its upper end bears against the under-side of the fixed abutment 18 on the upper end of the rod 17, and holds the head 17a of the rod in firm contact with the lower end of the sleeve 19, in order that the sleeve 19, the rod 17 and the collar 22 will slide vertically as a unit within the boss 12.

Vertical movement upwardly of the rod 17, through the link 16, arm 13 and shaft 9,

closes the gripping jaws 1—2 and 3—4 and vertical movement of the rod 17, etc. in a reverse direction, downwardly, opens the said jaws.

5 The vertical movement of the sleeve 19 and the elements 17 and 22 as a unit is accomplished by a gear segment 23, the teeth of which meshes with rack teeth 24 formed, in the present instance, directly on one side of 10 the sleeve 19.

The segment 23 is secured to one end of a horizontal shaft 27, on the opposite end of which is a spiral gear 25. The gear 25 meshes with a similar gear 26 secured to the 15 upper end of the vertical shaft 14. This shaft is adapted to be rotated in one direction at a predetermined time to raise the sleeve 19 to close the jaws 1—2 and 3—4 for gripping a stocking and the form thereon; and 20 at another predetermined time to be rotated in an opposite direction to lower the sleeve 19 to open the jaws 1—2 and 3—4 to release the stocking after the form has been withdrawn therefrom. Rotation of the shaft 14 25 is accomplished by mechanism forming no part of the present invention and has not been shown.

The shaft 14 operates continuously and in timed relation to the conveying mechanism 30 shown in the above mentioned patent and when forms emerge from the drier on which no stockings have been placed, it is desirable that such empty forms do not contact with the grippers 1—2 and 3—4 and for this purpose the jaws 1—2 and 3—4 are maintained in an open position while the other elements function in a normal manner in timed relation to the elements of the drier.

To prevent the jaws 1—2 and 3—4 from 40 closing, the collar 22 is turned about the axis of the rod 17, during which the cam face 21 of said collar slides downwardly on the cam surface 20 on the upper end of the sleeve 19, from the position shown in Figs. 5 and 6 to 45 the positions shown in Figs. 2 and 8, the rod 17 and the fixed abutment 18 on the upper end of the rod 17 at the same time moving downwardly from the position shown in Fig. 2 to the position shown in Fig. 8, the shaft 9 50 being thereby turned in a direction to open the jaws 1—2 and 3—4 if and when the sleeve 19 is moving or has moved upwardly in a normal jaw-closing operation.

It will be noted that in Figs. 1, 2, 5 and 8 of 55 the drawings, the shaft 27 has been turned to raise the sleeve 19 to its highest jaw closing position, and by reason of the said turning of the collar 22 the rod 17 has been lowered from the position shown in Figs. 2 and 5 to 60 the position shown in Fig. 8, whereby the jaws 1—2 and 3—4 have been moved from their closed positions in Figs. 2 and 3 to their open positions of Fig. 4, consequently when the sleeve 19 is lowered by reverse movement 65 of the shaft 27 the sleeve 19 will merely slide

idly down the rod 17 which remains stationary with the jaws in the open position, leaving the fixed abutment 18 spaced well above the upper end of the collar 22, so that when the sleeve 19 is again raised it slides upwardly 70 and idly on the rod 17 without affecting the quiescent position of the rod 17 and the jaws 1—2 and 3—4.

Turning of the collar 22 in an opposite direction, whereby the cam face 21 thereof slides on the cam face 20 on the upper end of the sleeve 19, again brings the sleeve 19 and collar 22 into full extended relation to each other, filling the space between the lower side of the fixed abutment 18 and the upper side 80 of the head 17a of the rod 17, thus the rod 17, the sleeve 19 and the collar 22 will again operate as a unit.

Difficulty has been encountered in maintaining the collar 22 in its fully extended 85 position when the unit, of which the collar is a part, is operating normally as above described for periodically opening and closing the jaws. The vibration of the machine tends to cause the collar 22 to rotate slightly about the rod 17, the cam surface 21 of the collar sliding down the cam surface of the sleeve 19 so that the jaws 1—2 and 3—4 do not close tightly upon a stocking inserted therebetween, thus the jaws lose their grip and do 90 not remove the stocking from the form.

One object of the present invention is to prevent the above noted accidental improper closing of the jaws and this object is attained by providing the collar, in the present instance, with a securing latch which will positively hold the sleeve against rotation when in its fully extending position with respect to the sleeve 19.

Referring to Figs. 5, 6 and 7, the collar 22 is provided with an operating handle 30 which is straddled, in the present instance by a spring-pressed latch lever 31, pivoted at 32 and provided above the handle with a thumb pad 33 and below the handle with a projection 34 which extends into a relatively close fitting aperture 35 formed in the upper end of the sleeve 19, so that when the collar 22 is rotated to extend the collar as above noted, the said collar will be prevented from rotating in a manner to permit the collar cam surface to slide down the cam surface of the sleeve 19 and thus effect improper closing of the jaws 1—2 and 3—4. A spring 131 tends to force the projection 34 into its receiving cavity 35 115 at all times.

The coacting cam surfaces 20 and 21 serve another purpose, aside from merely extending the collar 22 above the sleeve 19, i. e. these cam surfaces provide for a relatively fine adjustment of the elements for regulating the pressure exerted upon the stocking by the jaws 1—2 and 3—4, slight rotation of the collar minutely controlling the pressure exerted by the jaws on the stocking. With the 130

latch projection 34 closely fitting its retaining opening 35 even slight rotation of the collar 22 is prevented. It is therefore necessary to provide other adjustment of the rod 17 relative to the sleeve 19. Screw thread adjustment of the abutment 18 on the upper end of the rod 17 has proven unsatisfactory as it is impossible to maintain the adjustment due to the vibrations which loosens the nut 18 on the rod 17. In order to provide a positive adjustment between the rod 17 and the sleeve 19 to regulate the pressure of the jaws on the stocking, to regulate the closing of the jaws properly for stockings of different weights, and to provide for different thickness in the forms on which the stockings are placed, the nut 18 is positively secured to the rod 17, as for example by a pin 36, and the upper end of the collar 22 is provided with a cup-shaped cavity 37 which is adapted to receive a plurality of fillers 38 of various thickness of predetermined relative calibrations. Resting on top of the uppermost filling element is a free collar 39 which fits within the cup 37 and is provided with a flange 40 by which the free collar 39 may be readily raised out of the cup 37, whereby fillers of predetermined combinations may be placed in the base of the cup 37 to regulate the relation of the rod 17 relative to the sleeve 19, whereby the extent of closing of the jaws 1-2 and 3-4 may be minutely controlled.

Thus it will be seen that the coating cam surfaces 20 and 21 function to provide coarse adjustment of the rod 17, relative to the sleeve 19, to operatively connect the jaw controlling rod 17 with the actuating sleeve 19 for actuation of the jaws 1-2 and 3-4, and to disconnect the rod 17 from the actuating sleeve 19, while the fillers provide for delicate adjustment between the rod 17 and sleeve 19 for minutely controlling the closing of the jaws and the pressure exerted by the jaws on the stocking gripped between the jaws, and the latch 31 serves as a common means for maintaining both the coarse and fine adjustments of the jaw-controlling rod 17 relative to the jaw-actuating sleeve 19.

We claim:

1. In a machine for removing stockings from forms, the combination of a pair of cooperating jaws arranged to grip a stocking therebetween, actuating means for said jaws, jaw-controlling means intermediate the jaws and the jaw-actuating means, means for obtaining a coarse adjustment between the jaw-actuating means and the jaw-controlling means to close the jaws on said stocking, and means for positively maintaining said coarse adjustment.

2. In a machine for removing stockings from forms, the combination of a pair of cooperating jaws arranged to grip a stocking therebetween, actuating means for said jaws, jaw-controlling means intermediate the

jaws and the jaw-actuating means, means for obtaining a coarse adjustment between the jaw-actuating means and the jaw-controlling means to close the jaws on said stocking and means for obtaining a relatively fine adjustment between said jaw-actuating means and said jaw-controlling means to govern the extent of closing of said jaws minutely.

3. In a machine for removing stockings from forms, the combination of a pair of cooperating jaws arranged to grip a stocking therebetween, actuating means for said jaws, jaw-controlling means intermediate the jaws and the jaw-actuating means, means for obtaining a coarse adjustment between the jaw-actuating means and the jaw-controlling means to close the jaws on said stocking, means for obtaining a relatively fine adjustment between said jaw-actuating means and said jaw-controlling means to govern the extent of closing of said jaws minutely, and means for maintaining said adjustments.

4. In a machine for removing stockings from forms, the combination of a pair of cooperating jaws arranged to grip a stocking therebetween, actuating means for said jaws, jaw-controlling means intermediate the jaws and the jaw-actuating means, means for obtaining a coarse adjustment between the jaw-actuating means and the jaw-controlling means to close the jaws on said stocking, means for obtaining a relatively fine adjustment between said jaw-actuating means and said jaw-controlling means to govern the extent of closing of said jaws minutely, and means common to both of said adjusting means for maintaining said adjustments.

5. In a machine for removing stockings from forms, the combination of a pair of cooperating jaws arranged to grip a stocking therebetween, a slidable element for actuating said jaws, jaw-controlling element carried by said actuating element and arranged to slide thereon and relative thereto and operatively connected to said jaws, means for securing said relatively slidible elements together to function as a unit to operate said jaws, and means for locking said securing means to maintain the unitary actuation of said relatively slidible elements.

6. In a machine for removing stockings from forms, the combination of a pair of cooperating jaws arranged to grip a stocking therebetween, a slidable element for actuating said jaws, a jaw-controlling element carried by said actuating element and arranged to slide thereon and relative thereto and operatively connected to said jaws, means for securing said relatively slidible elements together to function as a unit to operate said jaws, and means intermediate the locking means and one of said sliding elements for minutely adjusting one of said sliding elements relative to the other of said sliding

elements to govern the extent of actuation of the jaws by said sliding elements.

7. In a machine for removing stockings from forms, the combination of a pair of cooperating jaws arranged to grip a stocking therebetween, a slidable element for actuating said jaws, a jaw-controlling element carried by said actuating element and arranged to slide thereon and relative thereto and operatively connected to said jaws, means for securing said relatively slidable elements together to function as a unit to operate said jaws, means intermediate the locking means and one of said sliding elements for minutely adjusting one of said sliding elements relative to the other of said sliding elements to govern the extent of actuation of the jaws by said sliding elements, and means for locking said securing means to maintain the adjustment between said sliding elements.

8. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a coarse adjusting element on said rod intermediate one end of the sleeve and one of said fixed abutments to provide a predetermined unitary movement of said sleeve and said rod, and means for locking said coarse adjusting means to maintain said coarse adjustment between the rod and the sleeve.

9. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a coarse adjusting element on said rod intermediate one end of the sleeve and one of said fixed abutments to provide a predetermined unitary movement of said sleeve and said rod, and means intermediate the coarse adjusting means and said fixed abutment for minutely governing the extent of unitary movement between the rod and the sleeve.

10. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a coarse adjust-

ing element on said rod intermediate one end of the sleeve and one of said fixed abutments to provide a predetermined unitary movement of said sleeve and said rod, means intermediate the coarse adjusting means and said fixed abutment for minutely governing the extent of unitary movement between the rod and the sleeve, and means for locking said coarse adjusting means to maintain the adjustment between the rod and the sleeve.

11. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a collar rotatably mounted on the rod intermediate one end of the sleeve and one of said fixed abutments, cooperating cam faces on the collar and the said end of the sleeve respectively for effecting a coarse adjustment between the sleeve and the fixed abutments on the rod, and means for locking the collar in adjusted position against relative rotation on the rod.

12. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a collar rotatably mounted on the rod intermediate one end of the sleeve and one of said fixed abutments, cooperating cam faces on the collar and the said end of the sleeve respectively for effecting a coarse adjustment between the sleeve and the fixed abutments on the rod, and means for locking the collar in adjusted position against relative rotation on the rod comprising a latch carried by the collar and arranged to cooperate with an abutment on the sleeve to prevent relative rotation between the collar and the sleeve.

13. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a collar rotatably mounted on the rod intermediate one end of the sleeve and one of said fixed abutments, cooperating cam faces on the collar and the said end of the sleeve respectively for effecting a coarse adjustment between the

- sleeve and the fixed abutments on the rod, relatively fine adjustment between the sleeve and the rod.
17. In a machine for removing stockings from forms, the combination of a pair of cooperating jaws arranged to grip a stocking therebetween, a control rod operatively connected to said jaws, a pair of relatively spaced abutments carried by and fixed to said control rod, an actuating sleeve slidably mounted on said control rod intermediate said fixed abutments, means for longitudinally reciprocating said sleeve on said rod, a collar rotatably mounted on the rod intermediate one end of the sleeve and one of said fixed abutments, cooperating cam faces on the collar and the said end of the sleeve respectively for effecting a coarse adjustment between the sleeve and the fixed abutments on the rod, a cup formed in the end of the collar adjacent one of said fixed abutments, a free collar on the rod intermediate the base of the cup and said fixed abutment, and a plurality of thin interchangeable fillers in the cup between the base thereof and the free collar, for obtaining relatively fine adjustment of the sleeve relative to the rod. 70
